UNITED STATES PATENT OFFICE.

HOMER WALTER JONES, OF JACKSON HEIGHTS, NEW YORK, ASSIGNOR TO NATIONAL CARBON COMPANY, INC., A CORPORATION OF NEW YORK.

BATTERY HAND LAMP.

Application filed March 31, 1926. Serial No. 98,805.

This invention relates to battery hand lamps, flashlights and the like, and more particularly to improved means whereby the reflector therein may be accurately positioned relatively to the lamp filament.

The filaments of the small incandescent lamps used in battery hand lamps are often not located exactly in the axis of the lamp. When such lamps are mounted in fixed relation to the usual reflector, it often happens that the major part or all of the filament is out of center with the reflector axis, especially as there are also liable to be slight inaccuracies in other parts of the hand lamp. The reflected light beam may therefore be distorted or diffused when a concentrated beam is desired.

The object of this invention is to compensate for such inaccuracies by providing a hand lamp in which the reflector is adjustable transversely of the axis of the lamp so that the axis of the reflector may be positioned to pass through the central portion of the lamp filament.

The above and other objects and the novel features of this invention will be apparent from the following description, taken with the drawings, in which:

Fig. 1 is a central longitudinal sectional view of a hand lamp embodying my invention, and

Fig. 2 is a detail sectional view on the line 2—2 of Fig. 1.

In the drawings, C designates the usual tubular casing of metal or fiber that contains a battery B of cylindrical dry cells to furnish the current to light the filament of the incandescent lamp L. The rear end of the casing is threaded to receive a threaded bottom cap 11 which carries therein a conductive metal shell 12 arranged to engage the bottom of the battery.

The front end of the casing is desirably expanded and threaded, as at 13, to frictionally retain an insulating supporting tube T that seats upon an interior shoulder 14 at the inner end of the expanded section. Indentations or beads 15 may be pressed into the part 13 and the tube T to more securely hold the tube in place. The tube T supports the guide G which carries an axially adjustable lamp holder H for a lamp L having a filament L'. The center electrode B' of the battery engages the contact J which is carried by the lamp holder

H. The battery and lamp holder are adjustable axially of the casing as a unit by the rotation of the bottom cap 11,—a spring S being compressed during forward movement of the lamp holder, and expanding to move the holder and lamp in the reverse direction. The guide G has a flaring portion 16 that closes the end of the tube T, and a cylindrical portion 17 of the guide is secured to the inner wall of the tube, as by rivets or indentations 18. A flange 19 on the part 17 engages the end of the tube. The guide and lamp holder assembly are more fully shown and described in an application Ser. No. 96,598, filed Mar. 22, 1926, in the name of Ralph R. Smith.

The reflector and lens assembly is carried on the front end of the casing C by means of a sleeve fitting F which is threaded at 20 to interfit with the threaded part 13. The outer extremity of the sleeve F has an out-turned flange 22 that provides a seat or supporting surface for the annular washer 23 upon which seats the peripheral flange 24 of the reflector R. The lens or cover glass E rests on the flange 24,—the lens E, reflector R and washer 23 being normally clamped tightly against the flange 22 by the lens ring N. The lens ring has an inwardly tapered part 26 which engages the outer beveled periphery of the lens E, and at its opposite end has a threaded skirt 27 that is adapted to interfit with a similarly threaded portion of an adjustable locking ring K. The locking ring K surrounds the sleeve F within the ring N and just behind the exterior flange 22, and its end is arranged to frictionally engage the latter to securely hold the reflector and lens assembly in any adjusted position when the lens ring has been tightened. The sleeve F desirably has two diametrically located ribs 30 adapted to fit into diametrically disposed recesses 31 in the locking ring K to keep the latter from turning when the lens ring N is screwed onto and off of the ring K.

Between its tapering part 26 and threaded skirt 27 the lens ring N has an interior groove 28 that is sufficiently deep to receive and retain the outer peripheral edge of the annular washer 23 to prevent the accidental separation of the reflector and lens from the ring N when the latter is removed from the casing. However, the outer edge of the

washer is sufficiently flexible so that it may be forced at will inwardly over the shoulder 29 to release the reflector and lens from the lens ring when it is desired to clean these parts. The inner edge of the washer engages the reflector and its outer edge engages the bottom of the groove 28. The reflector and lens assembly is also removable from the casing by unscrewing the sleeve F.

10 The groove 28 is also of sufficient depth to permit the reflector and lens assembly, when loosened, to be shifted a short distance laterally in any direction to position the axis of the reflector in line with the center of the 15 filament L' of the particular lamp that is mounted in the lamp holder. During such lateral adjustment the focal axis of the reflector is at all times parallel to the longitudinal axis of the lamp. To determine the 20 most desirable position for the reflector, the lamp is lighted and by trial, i. e. by setting the reflector in a number of different positions, that position should be selected which produces the narrowest possible beam of 25 light. During this adjustment of the lens ring, reflector and lens, the lens ring is unscrewed to sufficiently loosen the locking ring K so that the latter may be shifted laterally with the reflector and lens ring.

30 When the desired lateral adjustment of the reflector has been obtained, the lens ring is screwed inwardly along the locking ring which, when tightened, draws the end of the latter firmly against the under side of 35 the flange 22. Whenever a new lamp is inserted in the holder H to replace a defective or broken lamp, the foregoing adjustment of the reflector is repeated, in order to place the axis of the reflector in line with the central portion of the filament of the new lamp.

40 The lamp and its holder may then be adjusted in either direction along the reflector axis by turning the bottom cap 11 in the proper direction.

45 Various changes may be made in the details of the structure shown without departing from the principles of the invention. For example, other means may be employed for focusing the lamp longitudinally, and 50 the cooperating lens ring and locking ring may take other forms.

I claim:

1. A battery hand lamp comprising the combination of a casing; an incandescent lamp mounted therein; a reflector having its focal axis at all times parallel to the longitudinal axis of said lamp but laterally adjustable relatively to said lamp axis; a lens ring adjustable with said reflector; and 55 means operable to clamp said ring and reflector in any of their adjusted positions.

2. A battery hand lamp comprising the combination of a casing having a flange; an incandescent lamp mounted in said casing; 60 a reflector having its focal axis at all times

parallel to the longitudinal axis of said lamp but laterally adjustable relatively to said lamp axis; a lens in front of said reflector; a lens ring laterally adjustable with said reflector; and a ring cooperating with said flange and said lens ring to clamp said reflector in any one of its adjusted positions.

3. A battery hand lamp comprising the combination of a casing carrying a flange; an incandescent lamp mounted in said casing; a reflector laterally adjustable relatively to the longitudinal axis of said lamp; a lens ring laterally adjustable with said reflector; and a clamping ring engaging said lens ring and bearing against said flange 75 to secure said reflector in any one of its adjusted positions.

4. A battery hand lamp according to claim 3, wherein said clamping ring and said lens ring are connected together by interfitting threads.

5. A battery hand lamp according to claim 3, wherein said flange projects outwardly and said lens ring has a groove facing 80 said flange.

6. A battery hand lamp according to claim 3, wherein said lens ring has a threaded skirt, said reflector is seated on one side of said flange, and said clamping ring engages the other side of said flange and has threads 85 interfitting with said threaded skirt.

7. A battery hand lamp according to claim 3, wherein said clamping ring is axially adjustable along said casing but non-rotatable relatively thereto.

8. A battery hand lamp comprising the combination of a casing; a sleeve removably coupled to the casing and having an out-turned flange; an incandescent lamp mounted in said casing; a reflector seated on one side of said flange and laterally adjustable relatively to the longitudinal axis of said lamp; a lens mounted in front of said reflector; a lens ring adapted to hold 105 said lens and said reflector on said flange and laterally adjustable with said reflector, said lens ring having a groove facing said flange and a threaded skirt adjacent said groove; and a clamping ring disposed within said lens ring, engaging the other side of 110 said flange and having threads interfitting with said threaded skirt, said sleeve having rib means and said clamping ring having recess means fitting said rib means, whereby 115 said clamping ring is adjustable axially of said sleeve but held against rotation.

9. A battery hand lamp comprising the combination of a casing; an incandescent lamp mounted therein; means adapted to adjust said lamp longitudinally of its axis; a reflector laterally adjustable relatively to the longitudinal axis of said lamp; a lens ring adjustable with said reflector; and means operable to clamp said ring and reflector in any of their adjusted positions.

10. A battery hand lamp comprising the combination of a casing; a sleeve removably coupled to said casing; an incandescent lamp mounted in said casing coaxial with said sleeve; a reflector carried by said sleeve and laterally adjustable relatively to the axis of said sleeve and said lamp; a ring carried by said sleeve and adjustable laterally thereof with said reflector; and means operable to clamp said ring and reflector in ¹⁰ any of their adjusted positions.
- In testimony whereof, I affix my signature.

HOMER WALTER JONES.
